UNITED STATES PATENT OFFICE.

JOHN H. HAHN, OF SAUK CITY, WISCONSIN.

COUNTER DISPLAY CASE AND CABINET.

1,313,865.

Specification of Letters Patent.

Patented Aug. 19, 1919.

Application filed November 13, 1918. Serial No. 262,321.

To all whom it may concern:

Be it known that I, JOHN H. HAHN, a citizen of the United States, residing at Sauk City, in the county of Sauk and State 5 of Wisconsin, have invented new and useful Improvements in Counter Display Cases and Cabinets, of which the following is a specification.

This invention relates to counter display 10 cases and cabinets, the object of the invention being to produce a device of the character referred to, especially designed for displaying watches, knives, razors, spark plugs, and other small articles in a convenient, safe and attractive way, the cabinet 15 being also designed to contain a reserve stock of the articles on display, enabling articles sold from the display tray or rack to be replaced from the reserve stock.

With the above and other objects in view, 20 the invention consists in the construction, combination and arrangement of parts, as herein described, illustrated and claimed.

In the accompanying drawings:

Figure 1 is a front elevation of the display case.

Fig. 2 is a perspective view looking toward the rear thereof.

Fig. 3 is a vertical transverse section 30 through the cabinet or display case.

Fig. 4 is a perspective view of the combined rack and display supporting member, detached from the casing.

The display cabinet in one of the preferred 35 forms thereof comprises a box like casing which is shown attractively in the form of the radiator of a motor vehicle.

The casing of the cabinet comprises a glazed front wall 1, the upper portion 2 of 40 which is of arched or segmental formation as shown. The casing also comprises a bottom wall 3, side walls 4, and a rear wall 5 which is displaceable or adapted to be opened to give access to the interior of the casing, said back wall 5 being shown in Fig. 2 in the form of a door hinged to the back of the casing as shown at 6.

The interior of the cabinet is divided into 45 a front display compartment 7 and a rear reserve stock holding compartment 8 by

means of a vertical partition or false back 9 which may be of sheet metal or other suitable material.

Normally contained within the display compartment 7 is a combined article holding 55 tray and supporting rack 10 which stands vertical and is formed around three of the sides thereof with a rim or flange 11. The combined tray and support is preferably lined with plush or velvet as indicated at 12. 60 At its top, the combined tray and supporting rack has a combined cap piece and prop or support 13 which projects rearwardly from the main body of the rack or tray 10, and, as shown in Fig. 4 serves to support 65 the body of the tray or rack at a convenient angle for the display of the articles contained thereon, also facilitating the removal and replacement of said articles which are shown as secured to the tray or supporting 70 rack by means of hooks 14. The cap 13 of the device corresponds in shape with the upper arched or segmental portion 2 of the casing and has a knob 15 extending upwardly therefrom which is adapted to be 75 grasped between the fingers for the purpose of removing and replacing the combined cap piece and prop or support which also acts as a closure for the top of the casing.

In withdrawing the tray or rack from the 80 casing, it is not necessary to disturb the articles carried thereby, nor the reserve stock in the rear compartment of the casing. If a sale is made, the salesman may replace any article or articles removed from the 85 display section from the reserve stock, the latter being removed from the casing by opening the door 5. By glazing the front of the cabinet, the articles may be conveniently and attractively displayed without 90 liability of their being removed or disturbed from their hooks by a prospective purchaser. The construction of the cabinet is preferably such as to render the same dust-proof, and may be finished in any enamel or varnish or manner desired.

I claim:—

A counter display cabinet embodying a box-like casing having a glazed front, a displaceable back, bottom and side walls, 100

and a vertical partition dividing the interior into a display compartment and a reserve stock compartment, and a vertically movable and displaceable combined article supporting rack and tray arranged between said front and partition and having at the

top thereof a backwardly projecting proping flange which constitutes a closing cap for the casing when the parts are assembled.

In testimony whereof I affix my signature. 10

JOHN H. HAHN.
